UNITED STATES PATENT OFFICE

1,981,704

SPRAY DEVICE

Lawrence H. Moore, Wichita, Kans.

Application March 29, 1932, Serial No. 601,811

3 Claims. (Cl. 299—140)

This invention relates to spraying devices and the primary object is to provide a novel form of spraying device for delivering liquid in an atomized form from a container.

- 5 The device is adapted for use in connection with any kind of liquid such as fungicides, insecticides, paints and the like but it is particularly adapted for use in connection with paint spraying devices. According to my invention a wide 10 swath can be sprayed on trees, flowers, or in the case of paint a relatively wide area will be covered and while the invention was particularly designed for use in painting railway rolling stock its adaptability for other purposes will be obvious as the nature of the invention is better understood, reference being had to the accompanying drawings in which:

Fig. 1 is a side elevational view of a spraying device constructed in accordance with my invention.

Fig. 2 is an elevational view of a slightly modified form of the invention.

Fig. 3 is a sectional view through the nozzle and nozzle fitting.

25 Fig. 4 is a detail view of one form of mixing disc.

Fig. 5 is a longitudinal sectional view through the form of nozzle used with the construction shown in Fig. 2.

30 Fig. 6 is a sectional view on the line 6—6 in Fig. 3 and the line 6—6 in Fig. 5.

Fig. 7 is a longitudinal sectional view through the atomizing gun.

Fig. 8 is an edge view of the gun.

35 Fig. 9 is a sectional view on the line 9—9 of Fig. 7 showing the gun and trigger lever in elevation.

Fig. 10 is a sectional view on the line 10—10 of Fig. 7.

40 Fig. 11 is a sectional view on the line 11—11 of Fig. 7.

The liquid, for example, paint, is in a closed container under pressure and the air is supplied under pressure from any suitable source. There 45 is a flexible tube 1 connected to the air source and a similar tube 2 connected to the liquid source. These tubes are in turn connected to the gun casing 3 by means of nipples 4 and 5. The ends of the tubes can be fastened to the nipples 50 by clamping bands 6 and 7. The gun casing is provided with an air chamber or bore 8 having two branches indicated at 9 and 10. The air is normally closed off from the branch 10 by a plug valve 11 adapted to be seated on the seat 55 12 (see Fig. 11). In the branch 9 is a bushing

13 having a stuffing box 14, through which a valve stem 15 projects. The valve stem carries a valve 16 adapted to be urged into closed position on the end of the bushing by an expansion spring 17 and it can be moved off its seat by the trigger lever 18, pivoted at 19 and having a grip handle 20 adjacent to the narrow portion of the gun. When the valve 16 is unseated the air can pass through the opening 21 in the bushing into chamber 22 and be delivered in to 60 the outer air tube 23 mounted in the gun casing. The amount of air passed through the bushing will be governed by the plug valve 24 which controls the size of the opening at 21. The plug valve 11 will normally be seated so that air 70 will pass only through the bushing. The liquid is delivered into the bore or passageway 25 in the gun casing and into the bushing 26 having a stuffing box 27 to receive a valve stem 28 provided with a valve 29 to close the end of the 75 bushing by the spring 30. The valve can be unseated by the trigger lever 18 which has a screw adjustment 31 to vary the amplitude of movement of the valve. The air valve will be opened slightly in advance of the liquid valve and when the valve 29 is unseated the liquid will pass into the bushing out through opening 32 into chamber 33 to discharge into the inner tube 34 surrounded by the tube 23. The effective port area of the opening 32 can be controlled by the plug valve 80 35 (see Fig. 10). It will be noticed that the trigger lever has a curved offset portion 36 to allow it to clear the tube 23. The tube 23 is connected to a nozzle cap 37 (see Fig. 3) to deliver air to the passageway 38, 39, through the 85 perforated conical disc 40, and out through the nozzle 41 screwed thereon.

The disc is provided with notches 42 and 43 to allow the disc to be inserted in the cap. The notches receive the projections 44 and 45 and then by turning the disc the cam edges adjacent to the disc will ride under the projections to securely hold the disc in place. This will be effected because the projections are in the form of heads which can overlap the cam edges of the disc as shown in Fig. 6. The liquid is delivered through the tube 34 to passageway 46 to the chamber 47 where it is mixed with the air and the combined air and liquid is forced together in a commingled state through the orifice 100 in the disc 40 so that the air will carry the liquid through the slit 48 in the nozzle. The edge of the slit is flared and the slit extends practically across the face of the nozzle so that a relatively wide atomizing swath is provided. The plug 105 49 110

is provided so that the passageway 39 can be cored or drilled and then the end is closed.

From the foregoing it will be apparent that the air and liquid will be delivered to the nozzle 5 under pressure where the fluid will be broken up and commingled by the disc causing the liquid to be discharged in an atomized condition under pressure. The tubes 23 and 34 will ordinarily be long enough so that the nozzle may be swung 10 to deliver paint or other liquid over a relatively wide area without the necessity of the operator changing his position. When it is desired to clean the gun and particularly the nozzle, the valves 16 and 29 will be seated and the operator 15 will unseat the plug valve 11 manually so that air blown up through the paint tube 34 will force all accumulations out of the tube and out of the nozzle. This is an important feature of the invention because it eliminates the possibility 20 of any of the passageways or the nozzle becoming clogged.

In Fig. 2 I have shown a modified form of spraying device in which the air tube 50 is provided with a hand valve 51 and the paint tube 25 52 is provided with a similar valve 53. These tubes are associated with a slightly modified form 30 of nozzle cap shown in Fig. 5 as receiving the threaded ends of the tubes 50 and 52 and having a chamber 54 provided at one end with a web 55 having a central opening 56 adjacent to the disc 57 which can correspond in structure to the disc 40 shown in Fig. 4.

The nozzle 41 is the same construction as the nozzle shown in Fig. 3. The structure disclosed 35 in Figures 2 and 5 is a less expensive one than that previously described and by reference to Fig. 5 it will be obvious that the liquid and air will merge in the chamber 54, pass through the opening 56 and be commingled by the perforated conical disc 57 so that the liquid will emerge through 40 the nozzle opening in a fine spray providing a relatively wide swath. The proportions of air and liquid as well as the volume passing through 45 the pipes or tubes 50 and 52 will be controlled by the hand valves 51 and 53.

In actual practice I have found that the best results are obtained by proportioning the port 50 39 with port 48 in Fig. 3 or port 56 with the outlet port of nozzle in Fig. 5 so that the proper amount of air and liquid will be passed through to effect the desired atomization. For example, if the port 39 or 56 is too large, an excess amount

of paint will pass up into the head so that the requisite spray will not be had, in other words, the liquid will flood the head and it will be discharged in too solid a stream. If the ports 39 and 56 are very much smaller than the outlets 80 for the nozzles then the mixture will be so lean that very little paint will be carried through the head with the result that the surface will not be properly covered. Therefore I recommend that the ports 39, 56 or their equivalents be approximately of the same cross sectional area as the outlet for the nozzle. A good example is to have the ports 39 or 56 be $\frac{7}{32}$ " in diameter and to have the outlets for the nozzles of substantially the same port areas. In my own experience 90 this has given the best results, altho it may be found that slight deviations from the above recommended proportions can be had without materially affecting the results.

What I claim and desire to secure by Letters 95 Patent is:

1. A liquid spray device, comprising a head having a liquid inlet and an air inlet discharging into a mixing space, a nozzle on the head having a discharge opening communicating with the mixing space, a wall between the mixing space and the nozzle having openings through which the liquid and air pass to the nozzle, said wall consisting of a concavo-convex disc, the concave portion being directed toward the nozzle, and a 100 perforated wall in spaced relation with the first named wall in advance of the mixing space.

2. A liquid spray device, comprising a head having a liquid inlet and an air inlet discharging into a mixing chamber, a nozzle discharge for 110 the head, a wall in the head in advance of the mixing chamber having an opening, and a perforated wall spaced from the first named wall between said wall and the nozzle discharge.

3. A liquid spray device comprising a head having a liquid inlet and an air inlet discharging into a mixing space, a nozzle on the head having a discharge opening communicating with the mixing space, a concavo-convex wall between the mixing space and the nozzle having openings 115 through which the liquid and air may pass to the nozzle and a wall between the concavo-convex wall and the mixing space having a central opening concentric with the center of the concavo-convex wall.
